(57) **CLAIM**

The ornamental design for a handheld measuring instrument, as shown and described.

DESCRIPTION

FIG. 1 is a rear perspective view of the handheld measuring instrument;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof;

FIG. 7 is a front elevation view thereof; and,

FIG. 8 is a rear perspective view thereof, with a foldable stand deployed.

The broken lines are shown for environmental purposes only and form no part of the claimed design.
